ELECTRON BEAM CONTROLLING APPARATUS

Ronald C. Knechtli, Princeton, N. J., assignor to Radio Corporation of America, a corporation of Delaware

Application November 1, 1954, Serial No. 465,865

8 Claims. (Cl. 315—22)

The present invention relates to novel electron beam controlling apparatus and, more particularly, to apparatus for effecting controlled rotation of an electron beam in a cathode ray tube.

When the electron beam of a cathode ray tube is deflected in mutually perpendicular directions so as to scan a raster, the beam is subjected to forces which impart to it rotational movement in an amount and of a direction determined by the deflection fields. In a case of the usual circular-cross-section beam of a kinescope, such rotation is of no particular moment, insofar as image resolution is concerned, since a circular beam spot remains substantially circular even after such rotation. It has been found, however, that an elongated beam spot (e. g. elliptical or rectangular) affords the advantage of providing appreciably increased beam current, and, therefore, light output for a prescribed spot width and kinescope operating potential over that which may be obtained with a circular beam spot of equivalent "width" and under the same operating conditions.

As opposed to the case of a circular beam spot, deflection-caused rotation of an elongated beam spot is objectionable by reason of the fact that, where an elongated beam spot is used in a color kinescope of the so-called "line screen" variety, that is, one in which the screen is made of a plurality of phosphor strips of different color light emitting characteristics, such that the long dimension of the elongated spot is intended to remain parallel to the phosphor strips, beam rotation causes color dilution and is, therefore, quite undesirable.

Hence, it is a primary object of the present invention to provide novel means for compensating for the beam-rotating effects produced by scanning deflection fields in a cathode ray tube.

It has been found that deflection-caused beam spot rotation is a function, both as to magnitude and direction, of the position of the angularly deflected beam so that spot rotation is maximum at the corners of the raster. Conversely, spot rotation decreases as the beam approaches the center of the screen.

Thus it is another object of the present invention to provide novel means for compensating for beam spot rotation in a cathode ray tube, which compensation is a function of the deflected position of the beam, and, therefore, a function of the degree of correction or compensation necessary.

In general, the present invention provides novel means for compensating for the rotation of an electron beam in a cathode ray tube as a result of beam deflection, which means imparts to the beam a rotation opposite to the spot rotation caused by the deflecting magnetic field. That is to say, the compensatory rotation may be considered as being in the nature of a "de-rotation." In accordance with a specific form of the invention to be described herein, there is provided a cylindrical electromagnetic coil whose axis of cylindrical symmetry coincides with the axis of the electron beam between the electron gun and the raster scanning deflection yoke.

The coil is located around the neck of the kinescope between the gun and the deflection yoke and acts as a weak magnetic lens producing a rotation of the entire beam proportional to its magnetic field. Since, for a constant angle of deflection, the spot on the screen experiences a rotation substantially equal to the beam rotation, means are provided for controlling the current in the compensatory coil so that the beam rotation caused by that coil can compensate to any degree for the spot rotation caused by the deflection magnetic field. As will be more fully understood hereinafter, the rotation compensating coil of the present invention has only negligible effect upon focus of the beam within the useful range of rotation correction. By virtue of this fact, it is possible to maintain the longitudinal axis of an elongated beam spot parallel to a given reference line and over the entire screen of a kinescope while not appreciably defocusing the spot.

Additional objects and advantages of the present invention will become apparent to persons skilled in the art from a study of the following detailed description of the accompanying drawing, in which:

Fig. 1 is a block and schematic diagram of a television receiver including an image reproducing kinescope with which there is associated the beam spot rotation compensating apparatus of the present invention;

Fig. 2 is a front elevational view of the screen of the kinescope of Fig. 1 showing, in an exaggerated manner, the effects of beam rotation as a result of deflection; and

Fig. 3 illustrates a series of waveforms useful in an understanding of the invention.

While the invention will be described herein, in order to illustrate its utility, in connection with a color television kinescope of the horizontal line screen variety, its applicability to other forms of cathode ray tubes (including vertical line screen tubes in which the longitudinal axis of an elongated beam would normally be vertical) should be borne in mind. In the showing of Fig. 1, color television broadcast signals are intercepted

by an antenna 10 and applied to the input terminals of a color television receiver 12 which may be of any suitable form capable of operating upon such received signals. The video signals representative of the several selected component colors of the television image are

derived from the composite received signals and applied via leads 14 and 16 to the cathode 18 and control electrode 20 of a color kinescope 22. In the interest of completeness of description, it is to be noted that the kinescope 22 includes, in addition to the cathode and control electrode, a screen grid 24, focusing electrode 26 and final anode 28 which may be, as shown, in the form of a conductive wall coating. Suitable operating potentials are applied to the various electrodes of the kinescope in a conventional manner so that a beam of electrons

from the cathode 18 is caused to travel toward the phosphor screen 30.

The beam of electrons (not shown) is caused to scan a raster on the screen 30 by means of mutually perpendicular magnetic deflecting fields produced by an electromagnetic deflection yoke 32. The yoke 32 is illustrated as receiving suitable deflection currents of television line and field frequencies from horizontal and vertical deflection circuits 33 and 34, respectively, which are synchronized with the transmitter by means of signals derived in the receiver 12 and applied to them for synchronization. As thus far described, the apparatus of Fig. 1 is in accordance with conventional television practice and need not, therefore, be described in detail here.

Fig. 2 illustrates in an exaggerated fashion the front view of the phosphor screen 30 of the kinescope of Fig. 1 and shows several exemplary beam spots for different deflected positions of the electron beam. As will be under-

stood from the showing of Fig. 2, the phosphor screen 30 is made up of a plurality of horizontal strips of phosphor of different color light emitting characteristics. As the beam is deflected from left to right along the horizontal center line of the screen, no rotation thereof is caused by the deflection fields. Similarly, no rotation of the beam is present when the beam is deflected upwardly or downwardly along the vertical center line of the screen, this fact being indicated in the drawing. As the beam is deflected outwardly from the center toward one of the corners of the screen, however, the beam and, therefore, its spot, are rotated through an angle which is proportional to the angle of deflection (both horizontally and vertically). Thus, the closer that a beam spot is toward one of the corners of the screen, the greater is the amount of rotation imparted to it. Moreover, it will be seen from Fig. 2 that, if the screen be divided into its four quadrants, adjacent quadrants are "mirror images" of each other. Stated otherwise, as the beam is deflected toward the upper right corner of the raster as shown in Fig. 2, the beam spot experiences a gradually increasing counter-clockwise rotation. As the beam is deflected toward the upper left hand corner of the screen, however, the beam spot experiences an increasing clockwise rotation. In a similar manner, the beam spot is rotated in a clockwise manner and a counter-clockwise manner as it approaches the lower righthand and lower lefthand corners, respectively.

Such rotation of an electron beam as had been described is particularly objectionable in a case of a color kinescope of the type shown, since, as will be understood from the drawing, rotation of the beam spot causes the spot to illuminate two or more of the phosphor strips simultaneously, thereby producing color dilution.

Since, as has been stated, beam spot rotation of the type in question results from the action of the electromagnetic deflection fields, the present invention provides means for compensating for the beam-rotating of the deflection fields. Apparatus in accordance with the principles of the invention is illustrated in Fig. 1 and comprises the cylindrical electromagnetic coil 40 surrounding the neck of the kinescope between the source of electrons (i. e. the cathode 18) and the deflection yoke 32. The longitudinal or central axis of the compensating coil 40 is substantially coincident with the axis of the electron beam within the coil. When current is passed through the coil 40 there is produced a magnetic field whose lines of flux are generally axial of the tube 22. As will be appreciated, axial magnetic fields of special design are employed in many cases for beam focusing, a function not desired of the coil 40. In order to prevent the coil 40 from having any appreciable beam focusing or defocusing effect upon the electron beam while it performs its rotation-compensating function, the coil 40 should be designed as a weak magnetic lens. That is to say, the reciprocal of the focal length "f" of the magnetic lens afforded by the coils should be a maximum. The following equation is useful in expressing the relationship of the focal length "f" of a coil as a function of the magnetic field which it produces:

$$(1) \quad \frac{1}{f} = \frac{e}{8V} \int_{-\infty}^{+\infty} B_z^2 dz$$

where "e" is the charge of an electron, "m" is the mass of an electron, "V" is the potential of the electron beam at the coil with respect to the cathode of the tube, B_z is the axial component of the magnetic field on the axis of the coil, and "z" is the coordinate parallel to the axis of the coil.

The angle of rotation experienced by an electron beam

passing through a coil of the type shown in Fig. 1 may be expressed as follows:

$$5 (2) \quad \theta = \frac{e}{m} \int_{-\infty}^{+\infty} B_z dz$$

$$2\sqrt{2\frac{e}{m}V}$$

10 Since it is desired, in accordance with the invention, to impart various amounts of rotation to an electron beam while not appreciably affecting its focus, the quantity

$$\frac{1}{f}$$

15 in Equation 1 must be minimized for a given value of θ of Equation 2 (i. e., minimum lens action for a given angle of rotation). From the foregoing equations, it may be noted that, when the angle θ is prescribed, the quantity

$$\frac{1}{f}$$

20 will be smaller the longer the distance over which the quantity B_z is appreciably different from zero. In an ideal case, when B_z is assumed equal to a constant B_0 over an effective length "L" of the coil and equal to zero elsewhere, Equations 1 and 2 may be integrated as indicated. Equation 1 is then reduced to the following form:

$$30 (3) \quad \frac{1}{f} = \frac{e}{8V} \cdot B_0^2 L$$

Similarly, Equation 2 is reduced to the following form:

$$35 (4) \quad |\theta| = \frac{e}{2\sqrt{2\frac{e}{m}V}} \cdot BL$$

40 By dividing Equation 3 by Equation 4 after squaring both sides of the latter, the result of the operations is as follows:

$$45 (5) \quad \frac{1}{f} = \frac{\theta^2}{L}$$

45 The foregoing relations illustrate the fact that, for an optimum design, the rotation-compensating coils should be as long as possible for a given angle θ . It has been found, for example, that where the length of the coil L is greater than one inch, the lens action (i. e., focusing action) of the compensating coil is substantially negligible for angles of rotation up to 10°, an amount of correctional rotation which has been found to be sufficient for practical applications.

50 Once the proper length of the coil 40 has been determined in accordance with the foregoing relationships, the strength of the magnetic field required for given angles of rotation may be found through the use of Equation 2 supra.

55 Insofar as the energization of the rotation compensating coil 40 is concerned, the angle of rotation of a rectangular spot as a function of deflection has been found to be, as a first approximation, proportional to the algebraic product of the horizontal and vertical angles of deflection. Since the angle of corrective rotation produced by the compensating coil 40 is proportional to its magnetic field (in the absence of a saturated ferro-magnetic material), the corrective rotation is thus proportional to the current applied to the compensating coil.

60 Where I_h is the horizontal or line deflection current which is passed through the deflection yoke 32 for producing horizontal deflection of the electron beam and where I_v is the vertical deflection current passed through the yoke 32 for producing vertical beam deflection, the correction current I_c required for passage through the compensating coil may be expressed as follows for the

case in which the direction of the longitudinal axis of the elongated beam spot is required to remain constant over the entire screen:

$$I_c = I_0 + k I_h I_v \quad (6)$$

where I_0 is the direct current component of I_c . I_0 should be different from zero when the compensating coil must compensate, in addition to the rotation of the spot caused by deflection, for a misalignment between the longitudinal axis of the undeflected spot and the lines of the screen.

In the foregoing Equation 6, I_h and I_v are algebraic quantities representing sawtooth currents of zero average value (i. e., no direct current component), the period of I_h being equal to the television horizontal sweep period ($\frac{1}{15,750}$ second) and the period of I_v being equal to the vertical sweep period ($\frac{1}{60}$ second).

It is also to be noted that the sawtooth component of the correction current I_c should be equal in amplitude but opposite in sign (i. e., polarity) for any pair of horizontal lines of sweep which are symmetrical with respect to the horizontal center line of the screen.

In accordance with the foregoing requirements, Fig. 1 illustrates apparatus provided for energizing the coil 40 with suitable current for compensating for the beam rotation resulting from magnetic deflection fields. Current corresponding to the horizontal deflection current is caused to flow from the source 33 through the primary winding 44 of a transformer T, the secondary winding of which is indicated by the reference numeral 46. The upper end of the secondary winding 46 which is center tapped at 48 is connected to the control electrode 50 of a multigrid electron tube 52. The lower end of the winding 46 is similarly connected to the control electrode 54 of a second multigrid electron tube 56. The cathodes of the tubes 52 and 56 are connected to each other and to the positive terminal of a biasing battery 58 whose negative terminal is connected to the center tap of the secondary winding 46 and which serves to bias the control grids 50 and 54 so that they operate in accordance with Class A amplification principles.

Vertical frequency deflection currents from the source 34 are applied via the transformer T_2 to the screen electrodes 60 and 62, respectively, of the tubes 52 and 56. These latter electrodes are connected through the secondary winding of the transformer T_2 to a biasing battery 64 which biases the electrodes 60 and 62 for Class B operation. The anodes 66 and 68 of the two electron tubes are connected together and to the upper end of a common load resistor 70 whose other terminus is connected to a source of positive operating potential at the terminal 72 (+B). The common load terminal 74 of the amplifier tubes 52 and 56 is coupled via a capacitor 76 to one end of the winding 40, the other end of the winding 40 being connected to ground, as shown.

In the operation of the apparatus of Fig. 1 as thus far described, voltages such as those shown by waveforms (a) and (b) are applied, respectively, to the control electrodes 50 and 54 of the two electron tubes. At the same time, vertical frequency waveforms corresponding to those shown by curves (c) and (d) are applied to the screen electrodes 62 and 60, respectively.

By virtue of the Class B polarization of the screen electrodes of the tubes, the tube 52 will be rendered conductive during the first half of each television field (i. e., during the period t_1), while the tube 56 will be rendered conductive during the second half (i. e., period t_2) of each field. By virtue of the varying degree of amplification provided by the tubes to the horizontal frequency voltages of waveforms (a) and (b), the resultant waveform available at the output terminal 74, which resultant waveform constitutes the combined output of the two tubes, will be as shown in curve (e) of Fig. 3. Waveform (e) is, therefore, illustrative of the correction current applied to the compensating coil 40 and will also

be understood as being representative of the amount and direction of rotational correction imparted to the electron beam within the tube 22. That is, for each horizontal line scan, the amount of correction is its maximum at the extremities of the line and gradually decreases to zero at the center of the line. Moreover, the direction of correctional rotation changes as the scanning beam passes through the horizontal center of the raster.

From the foregoing, it will be understood that with a current of the waveform (e) of Fig. 3 passing through the coil 40, the axial magnetic field produced by that current will dynamically compensate for the rotational effects upon the beam produced by the deflection fields from the yoke 32. In other words, the auxiliary field produced by the coil 40 may be considered as a "de-rotating" field in that it imparts to the beam a rotation of the same magnitude but of the opposite direction from that which results from the deflection fields.

As has been mentioned in connection with Equation 6 supra, it is often desirable to provide a direct current component for the correction coil 40, as for the purpose of correcting for static misalignment between the longitudinal axis of the undeflected spot and a reference line drawn horizontally of the screen, for example. Such a direct current component is provided in the apparatus of Fig. 1 from a D. C. source 80 which will be understood as being variable in magnitude and reversible in direction and which is connected to that end of the coil winding 40 remote from the grounded end through a choke coil 82 which serves to prevent passage of the dynamic correcting current from the terminal 74 through the direct current source 80.

Those skilled in the art will recognize that the present invention provides relatively simple means for compensating both dynamically and statically for the rotation of an electron beam with respect to a target screen in a cathode ray tube and in a manner having no appreciable defocusing effect upon such beam.

Having thus described my invention, what I claim as new and desire to secure by Letters Patent is:

1. Electron beam controlling apparatus for use in conjunction with a cathode ray tube, said apparatus comprising: a substantially cylindrical electromagnetic coil adapted to surround the path of an electron beam; a source of line deflection signals; a source of field deflection signals; and means coupled to each of said signal sources and to said coil for passing through said coil a magnetic field-producing current generally proportional to the product of said line and field deflecting signals.

2. Electron beam controlling apparatus for use in conjunction with a cathode ray tube, said apparatus comprising: a substantially cylindrical electromagnetic coil adapted to surround the path of an electron beam; a source of line deflection signals; a source of field deflection signals; and means coupled to each of said signal sources and to said coil for passing through said coil a magnetic field-producing current generally proportional to the product of said line and field deflecting signals and continuously variable in intensity and direction as a function of such signals.

3. Electron beam controlling apparatus for use in conjunction with a cathode ray tube of the type having electromagnetic yoke means associated therewith for causing a beam produced therein to scan a raster in accordance with line and field deflection fields, such deflection fields being such as to produce rotation of such beam as a function of deflection, said apparatus comprising a generally cylindrical electromagnetic coil adapted to surround the path of such beam; a source of line deflection signals; a source of field deflection signals; and means coupled to each of said sources and to said electromagnetic coil for causing said coil to produce an electron beam rotating field which is variable as a function of such line and field deflection signals and which is

capable of causing rotation of such beam in the same amount as but of the opposite direction from the rotation produced by such deflection fields.

4. Apparatus for compensating for rotation of an electron beam in a cathode ray tube resulting from raster-scanning electromagnetic fields applied to such beam in its passage toward a target screen, said apparatus comprising: a source of line scanning deflection signals; a source of field scanning deflection signals; electromagnetic field producing means for producing a substantially axial field in the path of such beam; and means for energizing said last-named means with current proportional to the algebraic product of such line and field scanning deflection signal in such manner as to produce rotation of such beam of such magnitude and sense as substantially to cancel such rotation resulting from raster scanning.

5. The invention as defined by claim 4 wherein said axial electromagnetic field producing means comprises a cylindrical coil having great enough axial length as to render its magnetic lens focusing effect negligible.

6. Electron beam controlling apparatus for use in conjunction with a cathode ray tube of the type having means associated therewith for causing a beam therein to scan a field raster made up of a plurality of lines, said apparatus comprising: a source of line rate deflection sawtooth signals; a source of field rate deflection sawtooth signals; an electron beam rotating field producing means, first and second amplifier having a common output terminal; means coupling said output terminal to said field producing means; and means for applying line and field deflection signals from said sources to each of said amplifier means in such manner that said amplifiers provide at said output terminal a waveform comprising a line rate sawtooth wave of gradually decreasing amplitude and of a certain polarity during the first half of each raster field and of gradually increasing amplitude and of the opposite polarity during the second half of each raster field.

7. Electron apparatus for use in conjunction with a cathode ray tube of the type having means associated therewith for causing a beam therein to scan a field raster made up of a plurality of lines, said apparatus comprising: a source of line rate deflection sawtooth signals; a

source of field rate sawtooth signals; voltage multiplying means having an output terminal; means for applying line and field deflection signals from said sources to said voltage multiplying means in such manner that said multiplying means provides at said output terminal a waveform comprising a line rate sawtooth wave of gradually decreasing amplitude and of a certain polarity during the first half of each raster field and of gradually increasing amplitude and of the opposite polarity during the second half of each raster field; means for producing an electron beam rotating field; and means coupling said output terminal of said multiplying means to said last-named means.

8. Electron beam controlling apparatus for use in conjunction with a cathode ray tube of the type having means associated therewith for causing a beam therein to scan a field raster made up of a plurality of lines, said apparatus comprising: a source of line rate deflection sawtooth signals; a source of field rate deflection sawtooth signals; an electron beam rotating field producing means comprising electromagnetic coil in the form of a cylindrical winding having substantial axial length; voltage multiplying means having an output terminal; means coupling said output terminal of said voltage multiplying means to said beam rotating field producing means; and means for applying line and field deflection signals from said sources to said voltage multiplying means in such manner that said multiplying means provides at said output and for passage through said winding a waveform comprising a line rate sawtooth wave of gradually decreasing amplitude and of a certain polarity during the first half of each raster field and of gradually increasing amplitude and of the opposite polarity during the second half of each raster field.
